UNITED STATES PATENT OFFICE.

CHARLES E. CHRISTMAN, OF SAN JOSE, CALIFORNIA, ASSIGNOR TO
CHRISTMAN MOTOR CARRIAGE CO., OF SAN JOSE, CALIFORNIA,
A CORPORATION OF WEST VIRGINIA.

MUFFLER.

SPECIFICATION forming part of Letters Patent No. 701,151, dated May 27, 1902.

Application filed January 20, 1902. Serial No. 90,488. (No model.)

To all whom it may concern:

Be it known that I, CHARLES E. CHRISTMAN, a citizen of the United States, residing at San Jose, in the county of Santa Clara and State 5 of California, have invented certain new and useful Improvements in Mufflers; and I do hereby declare that the following is a full, clear, and exact description of the same, reference being had to the annexed drawings, 10 making a part of this specification, and to the letters of reference marked thereon.

The present invention has relation to that class of devices usually termed "mufflers" and which are employed for deadening the 15 noise produced by steam, vapor, or gas discharged under pressure into the atmosphere, and also the present construction of muffler is designed more particularly as an adjunct or attachment to an automobile and applied 20 in connection with the exhaust-pipe thereof. It is equally applicable to any engine or other contrivance in which steam, vapor, or gas is used and in which the noise attending the escape thereof is required to be deadened to 25 render it less objectionable.

The invention consists in a muffler constructed substantially as shown in the drawings and hereinafter described.

Figure 1 of the drawings is a longitudinal 30 section of a muffler constructed in accordance with my invention; Fig. 2, a similar view taken at right angles to that of Fig. 1; Fig. 3, an end view thereof; Fig. 4, a view showing the discharge end of the muffler opposite to that of Fig. 3; Fig. 5, a cross-section taken on lines 5 5 of Figs. 1 and 2 and looking in the direction of the arrow and showing the relative position of the conducting-pipes and the discharge-pipes; Fig. 6, a cross- 35 section taken on line 6 6 of Figs. 1 and 2 and looking in the direction of the arrow and showing the discharge-pipes through which the steam, vapor, or gas is discharged through the end of the muffler into the atmosphere.

40 In the accompanying drawings, A represents an outer cylinder, and B the inner cylinder, of the muffler, which may be of any suitable diameter and length and connected together in any desirable manner found best 45 adapted to the purpose.

The heads a b of the inner cylinder B have openings, to either one of which may be coupled the usual exhaust-pipe, the opposite opening being closed by a suitable screw- 55 plug c.

A plurality of conducting-pipes C are located in the space between the walls of the outer cylinder A and inner cylinder B and are somewhat shorter than the length of the cylinders, so that the escape ends of the pipes 60 will discharge the steam, vapor, or gas within the space between the walls of the two cylinders near the ends thereof. The conducting-pipes C, which extend longitudinally and parallel with the two cylinders A B, communicate with the interior of the inner cylinder B, near one end thereof, through the medium of gooseneck couplings d or by any other means found most convenient to form a communication between the interior of the inner cylinder and the conducting-pipes, this means of communication (shown in the drawings) between the cylinder and pipes not being essential to the successful operation of the invention so long as means are provided for securing communication between the cylinder and pipes. A plurality of discharge-pipes D are also located in the space between the outer and inner cylinders A B, these pipes also extending longitudinally and parallel with the cylinders and somewhat shorter than the cylinders, as shown in Fig. 2 of the drawings. The discharge-pipes D, through which the steam, vapor, or gas is discharged into the atmosphere, extends through the head e of the outer cylinder A, and the pipes C are somewhat shorter than the cylinders. The open ends of the discharge-pipes, which are located in the space between the walls of the two cylinders, are at the opposite ends of the cylinders 85 to that of the discharge ends of the pipes C, the relative location of the pipes and their arrangement with relation to each other being clearly shown in Figs. 1 and 2 of the drawings. The exhaust steam, vapor, or gas will 90 pass from the exhaust-pipe into the interior of the cylinder B, as indicated by the arrows, and circulate therein and pass back to the end of the cylinder, where it finds an outlet through the goosenecks d, and into the con- 95 100

ducting-pipes C. The steam, vapor, or gas after entering the conducting-pipes C will pass along the same and out through the open ends thereof into the space between the cylinders A B and along in an opposite direction to the open ends of the discharge-pipes D and thence through said pipes out at the opposite ends thereof and into the atmosphere. The device is simple, durable, and practical, there being absolutely no noise to the exhaust when discharged into the muffler, the back pressure being brought to a minimum.

The discharge and conducting pipes being all parallel with the cylinders and arranged as hereinbefore described renders the muffler perfect in action and overcomes the defects hereinbefore experienced.

Having now fully described my invention, what I claim as new, and desire to secure by Letters Patent, is—

1. A muffler comprising an outer cylinder and an inner cylinder, means for connecting the exhaust with the inner cylinder, and a plurality of condensing-pipes and a plurality of discharge-pipes, the former communicating with the interior of the inner cylinder and the latter communicating with the atmos-

phere, and both sets of pipes located in the space between the inner and the outer cylinders, substantially as and for the purpose set forth.

2. A muffler comprising an outer cylinder and an inner cylinder, said inner cylinder provided with means for connecting with the exhaust-pipe, a plurality of conducting-pipes and a plurality of discharge-pipes located within the space between the two cylinders, the conducting-pipes communicating at one end with the interior of the inner cylinder and at their opposite ends communicating with the space between the two cylinders, and the discharge-pipes communicating at their opposite ends with the space between the two cylinders and with the atmosphere respectively, whereby the steam, vapor or gas is discharged into the same, substantially as and for the purpose specified.

In testimony that I claim the above I have hereunto subscribed my name in the presence of two witnesses.

CHARLES E. CHRISTMAN.
